UNITED STATES PATENT OFFICE.

WALTER S. BACHMAN, OF CHICAGO, ILLINOIS.

STERILIZING ATTACHMENT FOR WATER-SUPPLY PIPES.

Application filed January 12, 1922. Serial No. 528,875.

To all whom it may concern:

Be it known that I, WALTER S. BACHMAN, a citizen of the United States, and a resident of Chicago, in the county of Cook and State 5 of Illinois, have invented certain new and useful Improvements in Sterilizing Attachments for Water-Supply Pipes; and I do hereby declare that the following is a full, clear, and exact description thereof, reference being had to the accompanying drawings, and to the letters of reference marked thereon, which form a part of this specification.

This invention relates to improvements 15 in sterilizing attachments for water supply pipes and consists of the matters hereinafter described and more particularly pointed out in the appended claims.

The object of the invention is to provide 20 an improved construction for a sterilizing attachment such as is illustrated and described in U. S. Patent No. 1,321,586 granted to me on October 16, 1919.

The advantage of the present invention 25 will more fully appear as I proceed with my specification.

In the drawings:—

Fig. 1 is a view in side elevation of my 30 improved sterilizing attachment, interposed in a water pipe used in connection with a drinking water filter.

Fig. 2 is a vertical section through my improved sterilizing attachment on an enlarged scale, the plane of the section being 35 indicated by the line 2—2 of Fig. 1.

Fig. 3 is a view similar to that shown in Fig. 2 with one of the parts shown in a changed relation.

Fig. 4 is a horizontal section through the 40 attachment in a plane indicated by the line 4—4 of Fig. 2.

Referring now in detail to that embodiment of my invention illustrated in the accompanying drawings: 5 indicates a water 45 supply pipe and 6 indicates as a whole, my improved sterilizing attachment. As shown herein, the pipe 5 supplies water to a filter 7 for rendering the water fit for drinking purposes, but as is apparent, the invention is 50 not limited to use in connection with a drinking water filter, since it may be used in other places where its peculiar characteristics make it advantageous to do so. The outlet from the pipe 5 is controlled by a faucet 8 55 through which the water flows after passing through the filter.

My improved sterilizing attachment 6 includes an upright tubular, non-corrosive metal casing 9, which as shown is of a height greater than its diameter. Said casing is 60 closed at its ends by top and bottom screw threaded caps 10 and 11 respectively, the bottom cap preferably being conical or funnel-shaped in vertical section. The cap 10 has threaded into it a part 5^a of the pipe 5, 65 while the bottom cap 11 has threaded into it the other part 5^b of the pipe 5, which connects the interior of the casing 9 with the interior of the filter 7. In the pipe part 5^a is provided a union fitting 12 and above the 70 same a shut off valve 13, the purposes of which will presently appear.

Concentrically within the casing and resting upon the funnel shaped bottom wall of the bottom cap 11 is a tubular vessel 14 75 providing the container for a sterilizing agent, for example, a solution containing active chlorine. This vessel or container is preferably made of glass and is of a diameter somewhat less than that of the casing so as to leave an annular space 15 between it and the casing 9. Said container is held in proper spaced relation within the casing by means of radially spaced, inwardly extending lugs 9^a arranged near the top and bottom ends of the casing.

The bottom end of the container 14 is provided with a plurality of annularly spaced lugs 16 which depend below the integral bottom wall 17 of the container and bear upon the conical or funnel shaped bottom wall of the cap 11. The spaces or notches 16^a between said lugs 16, serve to connect the annular space 15 about the container with the space within the cap 11 below the container and thus with the pipe part 5^b connected with said cap. In the bottom wall 17, preferably in the vertical plane of the axis of the container, is provided a conical depression or recess 18 which includes a central depending boss 19 having a vertical hole or opening 20 of small diameter which provides an outlet for the container. The recess 18 is adapted to receive and hold a wad 21 of asbestos which acts to catch any sediment or solids discharged with the sterilizing agent, and thus prevent a building up of a deposit of such sediment about the discharge opening 20 as would choke and finally close off the same.

Removably attached to the open, top end of the container is a differential pressure

member in the form of an elongated water-proof bag 22, preferably made of rubber and closed at one end 23 and open at its other end 24. Said rubber bag is of a diameter approximating the inside diameter of the container and of a length approximating the height of said container. The closed end 23 is inserted into the container while the open end 24 is folded over the top end of said container, said folded-over part engaging about the outside surface of the top end of the container and being removably attached thereto, water-tight, by means of elastic bands or securing devices 25 which pass around the said folded-over part and top end of the container 14.

The operation of my improved sterilizing device is as follows: The container 14 is first charged with a sterilizing agent and in order to do this, it is removed from the casing 9 by unscrewing the top cap 10 therefrom, whereupon the container 14 may be withdrawn vertically from the casing. The securing devices or bands 25 are removed and the bag 22 is withdrawn from the container. The charge of sterilizing agent is then poured or otherwise introduced into said container. The closed end 23 of the bag is then inserted into the container and the open end 24 is folded over and is secured to the top end of the container, after which the container is replaced within the casing and the top cap applied thereto.

The pipe part 5^a is then connected by means of the union fitting to the main part 5 of the pipe line, leading to the filter, the valve 13 being first closed off to prevent the flow of water during the attachment of the sterilizing device.

When the container has thus been charged, the water-proof or rubber bag 22 will lay in folds upon the top of the sterilizing agent at the top end of the container. When the valve 13 is again opened, water will enter and fill the casing 9 and surround the container 14 and will tend to enter the container and thus exert its pressure upon the rubber bag and consequently upon the top end of the column of sterilizing agent in the container, until the normal pressure in the pipe 5 is attained both inside and outside of the container. Thus a pressure balance is imparted to the body of the sterilizing agent through said bag and the hole in the bottom end of the container. This pressure will of course maintain through the pipe part 5^b and filter 7 down to the faucet 8. The water and said sterilizing agent are kept separated from each other by the bag and thus there can be no mixing of the water and sterilizing agent at this end of the container, which of course would act to dilute the agent.

When the faucet 8 is opened, a differential pressure will be started at both top and bot-

tom of the container and in addition, the water in the casing 9, flowing through the spaces 16^a on the way to the faucet 8 will set up an aspirating action which will tend to draw or suck the liquid in the container, out through the asbestos strainer 21 and hole 20 in the bottom end of said container. As a result a minute quantity of the sterilizing agent is drawn out of the container and mixed with the water flowing on its way to the faucet, the amount taken from said container being accommodated for by the rubber bag, which readily unfolds or distends itself to take care of the level in the container, no matter what the same may be, as shown in Fig. 3.

With the faucet open, the water pressure on the bag will force some of the sterilizing agent out of the container and as soon as the faucet is closed, the pressure becomes balanced on each end of the column of agent so that the discharge of said agent will cease, with the flow of water from the casing 9 towards the faucet 8. Thus when the faucet 8 is opened, the differential pressure member 90 or bag 22 is active to discharge the agent and as soon as the faucet is again closed, said differential pressure member or bag immediately becomes inactive.

The opening 20 is made of such small cross section that but a small quantity of sterilizing agent is introduced into the water each time the faucet 8 is opened, said amount being so small that it will barely effect the taste of the water even when the usual and preferred sterilizing agent containing free chlorine is used. When a filter of the kind described is used, any evidence of chlorine will be entirely eliminated.

By the use of the asbestos strainer, the solids or sediments in the sterilizing agent are caught before they can enter the minute discharge opening 20, thus said solids or sediments cannot build up a deposit about the ends of said opening, as would tend to choke or stop up said opening.

The advantages of the improved construction are apparent. The sterilizing agent cannot become diluted nor can the discharge opening become clogged so as to impair the intended operation of the attachment. Said attachment operates automatically to discharge a small quantity of the sterilizing agent each time the faucet is opened, no matter what the level of the sterilizing agent may be in the container. Said container is easily removed for refilling, without loss of the sterilizing agent and may be readily cleaned. The strainer may also be easily renewed.

While in describing my invention, I have referred to the same as used in connection with a filter for drinking water purposes and I have referred to certain specific details of construction, I do not limit myself

thereto except as may be pointed out in the appended claims.

I claim as my invention:

1. A sterilizing attachment for water supply pipes, comprising a casing adapted to be interposed in a water supply line and to form a part thereof, means providing a container within the casing for a sterilizing agent, while at the same time permitting a free flow of water through said casing about the container, which has a small discharge opening at one end, a differential pressure member associated with the other end of the container for keeping the sterilizing agent separate from the water in the casing, said member being active under the pressure of the water when flowing through the casing to discharge a part of the sterilizing agent out through the discharge opening of the container into said water.

2. A sterilizing attachment for water supply pipes, comprising a casing adapted to be interposed in a water supply line and to form a part thereof, means providing a container within the casing for a sterilizing agent, while at the same time permitting a free flow of water through said casing about the container, which has a small discharge opening at one end, a differential pressure member associated with the other end of the container for keeping the sterilizing agent separate from the water in the casing, said member being active under the pressure of the water when flowing through the casing to discharge a part of the sterilizing agent out through the discharge opening of the container into said water, but being inactive to discharge said agent when no water is flowing through said casing.

3. A sterilizing attachment for water supply pipes, comprising a casing adapted to be interposed in a water supply line and to form a part thereof, means providing a container within the casing for a sterilizing agent, while at the same time permitting a free flow of water through said casing about the container, which has a small discharge opening at its bottom end, a differential pressure member in the top end of said container capable of being acted upon by the water pressure when a flow of water is set up through the casing, to force a part of the sterilizing agent out through said discharge opening into said water, said member keeping the sterilizing agent separated from the water at the top end of the casing.

4. A sterilizing attachment for water supply pipes, comprising a casing adapted to be interposed in a water supply line and to form a part thereof, means providing a container within the casing for a sterilizing agent, while at the same time permitting a free flow of water through said casing about the container, which has a small discharge opening at its bottom end, means associated

with the top end of the container which is influenced by the water pressure to discharge a part of the sterilizing agent out through the discharge opening, said means keeping the said agent and water at the top end of the container separated at all times, and a strainer in the bottom end of said container about said discharge opening.

5. A sterilizing attachment for water supply pipes, comprising a casing adapted to be interposed in a water supply line and to form a part thereof, means providing a container within the casing for a sterilizing agent, while at the same time permitting a free flow of water through said casing about the container, which has a small discharge opening at its bottom end, means associated with the top end of the container which is influenced by the water pressure to discharge a part of the sterilizing agent out through the discharge opening, said means keeping the said agent and water at the top end of the container separated at all times, and means for holding a wad of asbestos within the container about the discharge opening, for straining the sterilizing agent passing therethrough.

6. A sterilizing attachment for water supply pipes, comprising a casing adapted to be interposed in a water supply line and to form a part thereof, means providing a container within the casing for a sterilizing agent, while at the same time permitting a free flow of water through said casing about the container, which has a small discharge opening at its bottom end, a flexible water-proof member fixed to the top end of the container for keeping the water separated from the sterilizing agent, said flexible member being active under the pressure of water when flowing through the casing to discharge a quantity of the agent out through the discharge opening at the bottom end of the container.

7. A sterilizing attachment for water supply pipes, comprising a casing adapted to be interposed in a water supply line and to form a part thereof, means providing a container within the casing for a sterilizing agent, while at the same time permitting a free flow of water through said casing about the container, which has a small discharge opening at its bottom end, a water-proof bag removably attached to the top end of the container for keeping the water separated from the sterilizing agent, said bag being active under the pressure of the water when flowing through the casing to discharge a quantity of the agent out through the discharge opening at the bottom end of the container.

8. A device of the character described, comprising a tubular casing, top and bottom caps therefor, a container within the casing, said container being open at its top

end and closed at its bottom end, said bottom end resting on the bottom cap of the casing and having a recess therein and a small discharge opening, a strainer in said recess, means for holding the container in spaced relation with respect to the casing, and a water-proof bag removably attached to the top end of said container.

In testimony that I claim the foregoing as my invention, I affix my signature in the presence of two witnesses, this 20th day of December, A. D. 1921.

WALTER S. BACHMAN.
